UNITED STATES PATENT OFFICE.

ERNEST EDGAR DAGLISH AND WALTER LEONARD LORKIN, OF LONDON, ENGLAND.

WINDING MECHANISM.

1,207,141.

Specification of Letters Patent.

Patented Dec. 5, 1916.

Application filed February 16, 1914. Serial No. 819,038.

To all whom it may concern:

Be it known that we, ERNEST EDGAR DAGLISH and WALTER LEONARD LORKIN, both subjects of the King of Great Britain, residing at 2 and 3 Norfolk street, Strand, in the county of London, England, have invented certain new and useful Improvements in or Relating to Winding Mechanism, of which the following is a specification.

This invention relates to hand operated or power driven winding mechanism and is particularly intended for hand actuated brake mechanism of electric cars and other vehicles, such as that of the kind wherein the operating hand wheel or hand lever is connected to the chain drum of the brake by means of gearing, and in which two stops are employed the coöperation of which limits the unwinding or releasing movement of the hand wheel or lever.

The chief objects of the invention are to provide brake mechanism which as compared with such mechanism heretofore constructed will be more efficient in its action, more readily assembled and dismantled, of less weight, more compact and capable of being more readily adjusted.

In the accompanying drawings, Figure 1 is a side elevation showing a brake mechanism constructed in accordance with the invention, the mechanism being in position on a car platform. Fig. 2 is a section of the upper portion of Fig. 1. Fig. 3 is an underneath plan of a part of Fig. 1 hereinafter referred to. Figs. 4, 5, 6 and 7 are plans of other parts of Fig. 1, and Fig. 8 is an underneath plan of Fig. 7.

A is the car platform, B a shaft that is actuated by the operating hand wheel or lever.

C is the chain drum, and C', C² are the gear wheels connecting the shaft B to the said chain drum.

The lower end of the shaft B may be of square or other suitable cross-section to engage with a sleeve B' which forms part of or is connected to a ratchet wheel B². The lower part of the sleeve is in contact with a roller bearing B³ disposed between it and a boss D formed on a plate D' on which a pawl D² for coöoperating with the ratchet wheel B² is mounted (see Fig. 6). This plate is formed with four pillars D³ any

one of which is adapted to receive a stop D⁴ 55 for coöperating with a projection E formed on a loosely mounted cover E'. This cover is also formed with a stop E² (Figs. 2 and 3) adapted to coöperate with a pin F carried by a disk F' (Figs. 2 and 4) which is 60 loosely mounted between the cover E' and the ratchet wheel B². This disk is provided with a curved slot F² in which a pin B⁴ (Figs. 2 and 5) carried by the ratchet wheel B² is disposed. 65

From the above description it will be seen that the parts referred to constitute a form of lost motion arrangement similar to that set forth in the specification of our application Serial No. 792,203, the required adjustment being obtained by the placing of the stop D⁴ in one or other of the four pillars D³. When the shaft B is rotated the ratchet wheel B² moves with it and after having moved through nearly a complete revolution causes the pin B⁴ thereon to coöperate with the end of the slot F² thereby moving the plate F'. After a time the pin F engages with the projection E² and the cover E' is then moved until the 70 projection E comes into contact with the fixed stop D⁴. By these means the shaft B can move through approximately three complete revolutions in applying the brake and when the brake is released the chain 75 drum will be stopped in the original predetermined position. It will be observed that by reason of the stop D⁴ being mounted in one of the pillars D³ it can be readily removed from the top of the car platform so that it can be placed in another of the pillars when desired. The plate D' is 80 formed with lugs D⁵ (Figs. 1 and 6) by which it can be suitably fixed to the car 85 platform. 90

Arranged beneath the car platform is a plate G having a boss G' that bears against the lower face of the boss D. This boss G' is formed with a hole to rotatably receive the lower end of the shaft B and on the 100 lower end of this shaft the pinion C' is mounted, the said pinion being prevented from falling by a pin c passing transversely through the shaft B, or by other suitable means. In order to prevent the pinion C' 105 from falling even in the event of the pin c breaking or becoming detached, the said pinion is provided with an upper flange c'

bearing upon the upper face of the gear wheel C²; the latter may be made integral with or may be connected to the chain drum C and these two parts may be held in position by a bolt C³ passing through the car platform and the drum C and through a boss G² on the plate G. One end of the said plate G is formed with a pin g and the other end with two curved slots g' (Figs. 6, 7 and 8) concentric with the axis of the boss G'. A bolt d or the like (of which two are provided one passing through each of the lugs D⁴ of the plate D¹ and through each of the slots g') may be employed for holding the plate G in position. Prior to attaching the plate G to the car platform, the said plate may be rotated about the axis of the shaft B in order to bring the drum C more or less into position to suit the line of draft of the chain. This determines the points at which the bolt C³ and pin g engage with the platform, while the slots g' enable the adjustment of the plate G to take place after which the bolts d are tightened to assist in maintaining the plate in the adjusted position.

Preferably formed in one casting with the plate G is a yoke H which may be forked as shown in Fig. 8 and which serves to support the lower end of the pin C³. The aforesaid slots g' pass through the ends of the forked members of this yoke. Suitable webs h, h, (Fig. 1) may be cast on the yoke to give it the required rigidity.

What we claim and desire to secure by Letters Patent of the United States is:—

1. In winding mechanism, the combination with a stop carried by a moving part of said mechanism, a loosely mounted plate having a slot to receive said stop, a projection on said loosely mounted plate, a member that covers said plate, a fixed stop, and two projections on said member for coöperating respectively with the fixed stop and with the projection on the loosely mounted plate.

2. In winding mechanism, the combination with a stop carried by a moving part of said mechanism, a loosely mounted plate having a slot to receive said stop, a projection on said loosely mounted plate, a member that covers said plate, a fixed stop whose position can be readily adjusted, and two projections on said member for coöperating respectively with the fixed stop and with the projection on the loosely mounted plate.

3. In brake mechanism, the combination with the ratchet wheel, of a stop carried thereby, a loosely mounted plate having a slot to receive said stop, a projection on said loosely mounted plate, a member that covers said plate, a fixed stop, and two projections on said member for coöperating respectively with the fixed stop and with the projection on the loosely mounted plate.

4. In brake mechanism, the combination

with the ratchet wheel of a stop carried thereby, a loosely mounted plate having a slot to receive said stop, a projection on said loosely mounted plate, a member that covers said plate, a fixed plate upon which said member rests, a stop on said fixed plate, and two projections on said member for coöperating respectively with the stop on the fixed plate and with the projection on the loosely mounted plate.

5. In brake mechanism, the combination with the operating shaft, of a ratchet wheel moved by said shaft, a fixed member in which said ratchet wheel is rotatably mounted, a pawl for coöperating with said ratchet wheel, means for mounting said pawl on said member, a stop carried by said ratchet wheel, a loosely mounted plate having a slot to receive said stop, a projection on said loosely mounted plate, a member that covers said plate, a stop on said fixed member, and two projections on the member that covers said plate for coöperating respectively with the stop on the fixed member and with the projection on said plate.

6. In brake mechanism, the combination with the operating shaft, of a ratchet wheel moved by said shaft, a sleeve of said ratchet wheel, a fixed member, a hollow boss of said member for the reception of said sleeve, a pawl coöperating with said ratchet wheel, means for mounting said pawl on said member, a stop carried by said ratchet wheel, a loosely mounted plate having a slot to receive said stop, a projection on said loosely mounted plate, a member that covers said plate, a stop on said fixed member, and two projections on the member that covers said plate for coöperating respectively with the stop on the fixed member and with the projection on said plate.

7. In brake mechanism, the combination with the operating shaft, of a ratchet wheel moved by said shaft, a sleeve of said ratchet wheel, a fixed member, a hollow boss of said member for the reception of said sleeve, a roller bearing interposed between said boss and sleeve, a pawl coöperating with said ratchet wheel, means for mounting said pawl on said member, a stop carried by said ratchet wheel, a loosely mounted plate having a slot to receive said stop, a projection on said loosely mounted plate, a member that covers said plate, a stop on said fixed member, and two projections on the member that covers said plate for coöperating respectively with the stop on the fixed member and with the projection on said plate.

8. In a geared brake, the combination with the operating shaft, the chain drum and the connecting gearing, of a plate carrying the said parts, and means for connecting said plate to the structure on which the brake is mounted, said means comprising a member passing through the said structure

and through the chain drum and a member passing through said structure and through said plate.

9. In a geared brake, the combination with the operating shaft, the chain drum and the connecting gearing, of a plate carrying the said parts and having a curved slot therein, and means for connecting said plate to the structure on which the brake is mounted, said means comprising a member passing through the said structure and through the chain drum, and a member passing through said structure and through said slot.
10. In a geared brake, the combination with the operating shaft, the chain drum and the connecting gearing, of a plate carrying the said parts and having a curved slot therein, means for connecting said plate to the structure on which the brake is mounted, and a yoke connected to said plate and serving to support said chain drum, said connecting means comprising a member passing
15. 10. In a geared brake, the combination with the operating shaft, the chain drum and the connecting gearing, of a plate carrying the said parts and having a curved slot therein, means for connecting said plate to the structure on which the brake is mounted, and a yoke connected to said plate and serving to support said chain drum, said connecting means comprising a member passing

through said structure, the chain drum and the yoke, and a member passing through said structure and through said slot.

11. In a geared brake, the combination with the operating shaft, the chain drum and the connecting gearing, of a plate carrying the said parts and having a curved slot therein, means for connecting said plate to the structure on which the brake is mounted, and a forked yoke made integral with said plate and serving to support said chain drum, said connecting means comprising a member passing through the said structure, the chain drum and the yoke, and a member passing through said structure and through said slot.

In testimony whereof we affix our signatures in presence of two witnesses.
